AIR CONDITIONING

William L. McGrath, Syracuse, N. Y., assignor to
Carrier Corporation, Syracuse, N. Y., a corpo-
ration of Delaware

Application December 1, 1945, Serial No. 632,153

9 Claims. (Cl. 257—3)

1

This invention relates to air conditioning and to a method of operating an air conditioning system.

An air conditioning system in extensive use contemplates the division of a building into zones in accordance with the various heat loads present in the rooms of the building. In such system air from the exterior of the building is treated at a central conditioning point remote from the areas to be conditioned to compensate for ventilation and dehumidification requirements of the various zones. It is then distributed at relatively high static pressure and at relatively high velocity to a plurality of units disposed in and serving a plurality of areas to be conditioned in the various zones. The high pressure air supplied to each unit is discharged therein at high velocity inducing a relatively great circulation of air withdrawn from the areas served by the unit. The primary or high pressure air, and the secondary or induced air are then supplied to the conditioned area. Tempering means such as coils or the like are disposed in the various local units to effect heating or cooling of air circulated through the unit as required.

In the operation of the system cold water is furnished to the tempering means under summer conditions and warm water is furnished to the tempering means under winter conditions. Depending upon the heat load in each zone, cold or warm water may be supplied in winter or in summer. Under intermediate operating conditions, some zones of the building are supplied with warm water while other zones of the building may be supplied with cold water.

In an air conditioning system of this character cold water is passed through a coil or washer in the air conditioning equipment to dehumidify air before it is supplied to the various local units in areas to be conditioned. Such cold water serves to reduce the dew point of the air to a desired degree. The refrigeration equipment required to supply cold water for dehumidifying purposes is also required to supply cold water to the various local units in order to effect individual conditioning of each area in accordance with the variable heat factors present in such area. It will be appreciated refrigerating equipment of great capacity is required for such equipment must possess sufficient capacity to dehumidify the air and to effect local cooling under maximum load conditions. Consequently the cost of refrigerating equipment is a large factor in the initial cost of the air conditioning system and the operating expenses of such sys-

2

tem are great since the system does not possess sufficient flexibility to attain a reduction in operating costs commensurate with a reduction in the load imposed upon the system.

5 The chief object of the present invention is to provide a simplified circulating system for conditioning medium used in an air conditioning system.

An object of the invention is to provide a 10 simplified circulating system embodying control means which reduce the operating expenses of the system.

A further object is to provide a simplified air 15 conditioning system economical in initial and operating costs.

A still further object is to provide an air conditioning system in which the operating costs are reduced to a minimum.

A still further object is to provide a simplified 20 method of operation of an air conditioning system.

This invention relates to an air conditioning system including a simplified circulating system for conditioning medium. The circulating system 25 may comprise a source of supply of conditioning medium, means to direct conditioning medium from the supply through a heat exchange member of air conditioning apparatus, a line connecting the heat exchange member to a 30 common supply header, said header being adapted to supply conditioning medium to a plurality of zones of the air conditioning system, a supply main for each zone connected to the header, lines connecting the supply mains to heat 35 exchangers of conditioning units disposed in the areas to be conditioned, lines connecting the unit heat exchangers to a common return header, a return line connecting the return header and a second heat exchange member of the air conditioning apparatus, a line connecting the second 40 heat exchange member to the source of supply, and means for passing conditioning medium through the system.

This invention further relates to a method of 45 operation of an air conditioning system in which the steps comprise passing conditioning medium from a source of supply to a heat exchange member in heat exchange relation with air to be conditioned, then forwarding the conditioning medium to a common supply header, passing conditioning medium from the common header to a plurality of heat exchangers of units disposed in zones to be conditioned, collecting conditioning medium from the unit heat exchangers in 50 the zones in a common return header, passing

conditioning medium from the return header to a second heat exchanger disposed in heat exchange relation with the air to be conditioned and returning the conditioning medium to the source of supply.

The attached drawing illustrates diagrammatically a preferred embodiment of my invention.

Referring to the drawing, there is illustrated generally at 2 suitable air conditioning equipment for use in my invention. Such equipment may include a preheater 3, a fan 4 adapted to draw air from the exterior of the building into the conditioning equipment, sprays 5, a precooling coil 6, and a dehumidifying coil 7. Fan 4 passes air to be conditioned through sprays 5, coil 6 and coil 7; if desired reheaters 8 may be provided in the ducts (indicated by dotted lines) for supplying the conditioned air to conditioning units 9 disposed in areas 10 to be conditioned. The various areas 10 to be conditioned may be arranged in zones in accordance with the variable heat factors present in each area to be conditioned.

At 11 there is designated generally suitable refrigerating equipment adapted to cool conditioning medium, for example, water, and supply it to the coils 6 and 7 of air conditioning equipment 2 and heat exchange coils of units 9 in areas 10 to be conditioned. Such equipment may comprise a centrifugal compressor 12, actuated by a suitable motor or turbine 13, connected to a water cooler 14. A line 15 connects cooler 14 with the dehumidifying coil 7 of air conditioning equipment 2. Preferably, suitable means are provided to actuate compressor 12. Such means may comprise a control 16 adapted to govern the operation of turbine or motor 13 and which in turn is actuated by means of a thermostat 17 controlled by a bulb 18 placed in thermal contact with line 15.

Cold water from coil 7 passes through line 19 to a supply header 20 common to all the zones. Lines 21 connect header 20 with supply mains or risers 22 serving the zones to be conditioned. Valves 23 are disposed in lines 21 for a purpose hereinafter explained. Conditioning medium passes from supply mains 22 through lines 24 to heat exchange members 25 in the form of coils disposed in the units 9 in areas 10 to be conditioned. Cold water from heat exchangers 25 passes through lines 26, lines 27, lines 28 to a common return header 29. Valves 30 are disposed in lines 28 as hereinafter described.

Cold water from common return header 29 passes through return line 31 to the precooling coil 6 of air conditioning equipment 2. A pump 32 is disposed in line 31 as shown and a valve 33 is also disposed in line 31 between pump 32 and coil 6 for a purpose hereinafter described. From precooling coil 6, cold water passes through line 34 connecting coil 6 to the source of supply or cooler 14.

Under some conditions, for example when the various areas to be conditioned require only a small supply of cold water, the total flow of water through precooling coil 6 and dehumidifying coil 7 may be reduced. Under such conditions, the air being conditioned may not be conditioned adequately in accordance with the conditions encountered in the various areas. To obviate this disadvantage, I provide a bypass 35 connecting line 19 and return line 31. A valve 36 is disposed in bypass 35. Valve 36 is actuated by a pressure differential control 37 which is actuated by the difference in pressure of conditioning medium in

lines 34 and 15. Control 37 measures the difference in pressure on the circuit and as the pressure drops, indicating a reduction in water flow, valve 36 is opened and governed by control 37 to supply a substantially constant flow of cold water through coil 6 and coil 7.

Suitable air vents 38 may be disposed in the stub ends of supply mains 22 to permit air entrapped in the system to escape therefrom. Air vent 39 may be disposed in the return header for the same purpose. An expansion tank 40 is provided, header 29 being attached thereto by a line 41.

It will be appreciated that under winter conditions it may be desired to supply warm water to all of the zones. Under intermediate operating conditions it may be desirable to supply warm water to some of the zones. I provide a heater 42 containing a steam coil 43 adapted to heat water for supply to the various zones. The amount of steam passing through coil 43 may be governed by a suitable thermostat 44 controlled by a bulb 45 disposed in thermal contact with a line 46 connecting heater 42 with a supply header 47. Thermostat 44 is adapted to actuate a valve 48 disposed in steam line 49 to increase or to decrease the amount of steam passing through coil 43.

Warm water passes from heater 42 through line 46 to supply header 47 common to supply mains 22. Supply header 47 is connected to supply mains 22 by means of lines 50, in which are disposed valves 51. The warm water then passes through supply mains 22, lines 24, heat exchange members 25, lines 26, to lines 27. Lines 52 connect return header 53 with lines 27. Valves 54 are disposed in lines 52. Return header 53 is attached to expansion tank 40 by means of line 41 and line 55. A return line 56 connects return header 53 with a pump 57. A line 58 connects pump 57 with heater 42. Valve 33' is disposed in line 58 as hereinafter described.

When it is desired to supply hot water to the various zones, heater 42 supplies the hot water through line 46 to supply header 47 common to the zones. Hot water passes from header 47 through lines 50 to risers 22 disposed in the zones to be conditioned. Water then passes through lines 24, heat exchangers 25, lines 26, lines 27, lines 52 to return header 53. The water is passed from return header 53 through line 56, pump 57, line 58 to heater 42.

It will be understood that when it is desired to supply hot water to a zone, valves 51 and 54 will be opened and valves 23 and 30 will be closed. It is assumed that hot water is being supplied to all zones as is customary under winter operating conditions. When the system is operated during intermediate conditions, for example, in the spring or in the fall, hot water may be supplied to some of the zones while cold water is being supplied to the remaining zones.

Under conditions of maximum load requiring maximum cooling effect in the areas to be conditioned, it may be desired to use both lines 31 and 56 as cold water return lines, and in some cases to use pump 57 to impose additional pressure upon cold water in the system serving in effect as an auxiliary to pump 32. For this purpose a line 59 is provided containing valve 60. Such line connects return lines 31 and 56 on one side of pump 57. A second line 61 is also provided containing a valve 62 which also connects return line 31 and line 58. When it is desired to use both lines 31 and 56 as return lines,

valve 60 is opened, valves 62 and 33' being closed, to permit water from line 56 to flow into line 31. If it be desired to impose additional pressure upon the cold water circulating in the system, valve 60 is closed, valve 33' remaining closed, and valve 62 opened permitting pump 57 to impose additional pressure upon cold water in the system. It will be understood, of course, valves 54 in the various zones are open to permit cold water to flow to header 53 as well as to header 29 and to return through lines 56 and 31 to the precooling coil 6 of equipment 2 and then to the cooler 11.

While I have described the operation under conditions of maximum load requiring maximum cooling effect, it will be understood it may be desired to use both lines 31 and 56 as hot water return lines under conditions requiring maximum cooling effect. Under such conditions, valves 62 and 33 are closed and valves 60 and 33' are opened, to permit water from line 31 to flow into lines 56 and 58. If it be desired to impose additional pressure upon the hot water circulating in the system, valve 60 is closed, valve 33 remaining closed, and valve 62 is opened permitting pump 32 to impose additional pressure upon hot water in the system. The arrangement described is highly advantageous since it permits both pumps to be used to impose pressure when operating under conditions requiring maximum cooling effect or maximum heating effect and in addition permits one pump to serve as standby equipment for the other permitting repairs or replacement without discontinuance of operation of the system.

The circulating system proposed permits material operating economies to be effected in the operation of an air conditioning system. In an air conditioning system of the character described refrigeration equipment of less capacity may be used thus reducing the initial cost of the system. The system is more simple than systems heretofore proposed and consequently is more economical in operation. In addition to the various economies in initial cost and operating costs mentioned above, it will be understood that a considerable reduction in initial cost is effected by the manner in which the circulating system is constructed; the system provided by my invention eliminates approximately 50% or more of the piping heretofore deemed necessary in an air conditioning system and thus effects a saving not only in the cost of the piping but in the labor costs necessary to assemble the piping in the system.

While I have described a preferred embodiment of my invention, it will be understood my invention is not limited thereto since it may be otherwise embodied within the scope of the following claims.

I claim:

1. In an air conditioning system, the combination of means to condition primary air for supply to an area being conditioned, said means including a first heat exchange member, a second heat exchange member, means to pass air to be conditioned through said member, and a third heat exchange member disposed in heat exchange relation with secondary air from the area to be conditioned, a source of supply for conditioning medium, means for circulating conditioning medium from said source of supply through said first heat exchange member, through said third heat exchange member and then through said second heat exchange member

to return the conditioning medium to the source of supply, and means for supplying the conditioned primary and secondary air to the area to be conditioned.

5 2. In an air conditioning system for a plurality of enclosed areas disposed in zones, the combination of a first heat exchange member, a source of supply of conditioning medium, means connecting the supply to said heat exchange member, a supply header adapted to supply conditioning medium to a plurality of zones, a line connecting the heat exchange member to said supply header, a supply main for each zone connected to the header, unit heat exchangers disposed in the areas to be conditioned in heat exchange relation with secondary air to be conditioned, lines connecting the supply main to said unit heat exchangers, a return header, lines connecting the unit heat exchangers to said return header, a return line, a second heat exchange member, means for passing primary air in heat exchange relation with the first and second heat exchange members, said return line connecting the return header and said second heat exchange member, a line connecting the second heat exchange member with the source of supply means for passing conditioning medium through the system and means for supplying the conditioned primary and secondary air to the areas being conditioned.

10 3. A system according to claim 2 in which a bypass connects the supply header and the return line, a valve is disposed in said bypass, and means are provided to actuate said valve in response to a difference in pressure between conditioning medium in the first means and conditioning medium in the line connecting the second heat exchanger with the source of supply whereby upon a reduction in pressure, the valve is opened 15 to permit water to flow from the supply to maintain a substantially constant flow of conditioning medium through the second heat exchange member and the first heat exchange member.

15 4. In an air conditioning system for a plurality of enclosed areas disposed in zones, the combination of a source of supply of conditioning medium, said source of supply including a refrigeration system for cooling the conditioning medium to predetermined temperature, a coil, a line connecting the source of supply with said coil, a supply header adapted to supply conditioning medium to a plurality of zones, a second line connecting the coil and said supply header, a plurality of supply mains, lines connecting said supply header with said supply mains, each supply main being adapted to supply conditioning medium to a zone to be conditioned, unit coils disposed in the areas to be conditioned in heat exchange relation with secondary air to be conditioned, lines connecting the supply mains to said unit coils, a return header, lines connecting the unit coils with said return header, a second coil, a return line connecting the return header with said second coil, means for passing primary 20 air in heat exchange relation with said first and second coils, a line connecting said second coil with the source of supply, pump means for passing conditioning medium through the circulating system and means for supplying the conditioned primary and secondary air to the areas being conditioned.

25 5. A system according to claim 4 including a second source of supply for conditioning medium at a different temperature, a second supply header, a line connecting the second supply with

a second supply header, lines connecting the second supply header with said supply mains, a second return header, lines connecting the second return header with the lines connecting the unit heat exchangers to the first return header, a second return line connecting the second return header with the source of supply, and second pump means for passing the conditioning medium from the second source of supply through the system.

6. A system according to claim 5 in which valves are disposed in the lines connecting the supply mains and the first supply header, valves are disposed in the lines connecting the supply mains and the second supply header, valves are disposed in the lines connecting the unit heat exchangers with the first return header, valves are disposed in the lines connecting the unit heat exchangers with the second return header, movement of said valves permitting conditioning medium to be supplied to each zone from the first supply header or the second supply header and to return to its source of supply from the first return header or the second return header.

7. A system according to claim 6 in which a line is disposed in the system connecting the first return line and the second return line, a valve is provided in said line, a second line is disposed in the system connecting the first return line and the second return line, and a second valve is disposed in the second line, opening of the first valve permitting both return lines to be employed for returning conditioning medium to the second heat exchange member under peak load conditions while closing of the first valve and opening of the second valve permits the second pump means to serve as an auxiliary for the first pump means under peak load conditions.

8. A system according to claim 4 in which a bypass is provided connecting the return header and the return line, a valve is disposed in said bypass and control means for said valve are provided, said control means serving in response to a difference in pressure of conditioning medium in the first line and the line connecting second

coil with the source of supply to open said valve to permit conditioning medium from said supply header to flow into the return line.

9. In an air conditioning system, the combination of means to condition air, said means including a precooling coil, a dehumidifying coil and means to pass air to be conditioned through the coils; a plurality of areas to be conditioned, conditioning units in said areas adapted to receive conditioned air from the conditioning means, heat exchangers in said units, said areas being disposed in zones, means for supplying conditioned air to the unit, a source of supply for conditioning medium including a refrigeration system for cooling the conditioning medium to a predetermined temperature, a line connecting the source of supply with the dehumidifying coil, a common supply header, a second line connecting the dehumidifying coil with said common supply header, a plurality of supply mains connected to said header, each main being adapted to supply conditioning medium to said unit heat exchangers disposed in a zone, a common return header, a line connecting the unit heat exchangers with the return header, a return line connecting the precooling coil with the return header, a line connecting the precooling coil with the source of supply, pump means to pass conditioning medium throughout the system, a bypass connecting the supply header and the return line, a valve in said bypass and control means to open and to close said valve to maintain a substantially constant flow of conditioning medium through the precooling coil and the dehumidifying coil
